UNITED STATES PATENT OFFICE.

JOSHUA POOL AND JOSEPH POOL, OF GREENSBURG, INDIANA.

DESIGN FOR A MONUMENT.

SPECIFICATION forming part of Design No. 13,543, dated January 23, 1883.

Application filed October 18, 1882. Term of patent 14 years.

To all whom it may concern:

Be it known that we, JOSHUA POOL and JOSEPH POOL, both citizens of the United States, residing at Greensburg, in the county of Decatur and State of Indiana, have invented and produced a new and original Design for a Monument, of which the following is a specification, reference being had to the accompanying drawing, forming a part thereof, in which 5 to our newly-designed monument is fully illustrated by a single side elevation.

The leading feature of our new design consists in the arrangement or grouping of its component parts, and in the designs, in detail, 15 of said component parts, which will be readily understood by reference to the drawing, the whole being mounted on a square base, A, made in one or more pieces or sections.

The first section, B, of our monument or design is a base made square, and finished at the top corners to form plinths B', having vertical sides and beveled top edges adapted to receive the bases of the four pillars or columns, which are formed in each of the four corners 25 of the next die or section, C. These plinths B' may be square or cylindrical, and part of the space between them in the base B is flush or even with the surface, being relieved by a bevel the angle of which runs from the surface 30 of the base to the lower line of the die or section C, which rests on the base B. In each of the four corners of die C is cut or formed a pillar or column, C', which may be either square or round, and extends the whole height of the die. These pillars or columns may be formed 35 by cutting away the corners of the die, making a beveled cut from near each end of the pillar or column, as the case may be, and decreasing their diameters to the ends, as shown 40 at C'. These pillars or columns are also beveled toward their centers or middle portions, so as to form a collar, C², encircling the middle of each pillar or column. On each side of the die C is a raised panel.

45 The next section or cap, D, which is supported on the die, is square and finished on its under side to correspond with and fit the die on which it is mounted, and also the pillars or columns C'. The upper part of cap D is finished with semicircular arches or gables D' on

each of its four sides, and its four upper corners are cut out so as to form a plinth, D², in each of the four corners, said plinths having vertical sides to near the top of the cap, from which point they are beveled to fit the square 55 end of the spire E, which rests upon the cap, said bevels extending downward to the outer surface of cap D by the sides of the semicircular gables, as shown on the drawing; or the bevels may be cut so as to allow the plinths to extend 60 above the lay bevels, as in the base-piece B. The cap-plinths D² may be square or cylindrical, to conform to the other parts of the design.

The spire or top section, E, has a pillar or column, E', either square or round, in each of 65 its four corners, at its lower end or base, which extend part way up its length. It also has a projection, E'', on each of its four sides, extending upwardly part of its length and tapering, ending with a circular finish at the top of 70 each projection, as shown. The top or apex of the spire is finished with a lap-apex, E³, an urn, or any other suitable ornamental device.

Having thus described our design, we claim and desire to secure by Letters Patent of the 75 United States—

1. The design of a sectional monument, as shown, consisting of the square base B, fitted to the die C above, which, in its turn, is fitted to the cap D, surmounted by the spire E, with 80 its projections, the whole mounted on the square base A, as shown and described.

2. The design of the monument as a whole, with its various sections fitted together as described, having angles, curves, and faces arranged in relation to each other substantially 85 as shown and described.

3. The design of the base B, having plinths B' at the top corners, substantially as shown and described. 90

4. The design of the die C, having pillars or columns C' at its four corners, said pillars or columns having reduced ends C² and collars C³ encircling the middle part, substantially as shown and described.

5. The design of the cap D, having semicircular arches or gables D' on each of its four sides and plinths D² at each of its four corners, substantially as shown and described.

6. The design of the spire E, having a pillar 100

or column, E', in each of its four corners at the lower end or base, extending part way up its length, and having projections E² on each of its four sides, extending upwardly part of its length and tapering, ending with a circular finish at the top, the top or apex of the central spire being finished with an ornamental device or lap-apex, E³, substantially as shown and described.

Signed at Greensburg, Indiana, this 16th to day of October, 1882.
